UNITED STATES PATENT OFFICE.

EDMUND H. LUNKEN, OF CINCINNATI, OHIO.

WINDOW.

1,326,676.

Specification of Letters Patent. Patented Dec. 30, 1919.

Application filed August 13, 1918. Serial No. 249,728.

To all whom it may concern:

Be it known that I, EDMUND H. LUNKEN, a citizen of the United States, and a resident of Cincinnati, in the county of Hamilton and State of Ohio, have invented certain new and useful Improvements in Windows, of which the following is a full, clear, and exact description, reference being had to the accompanying drawing, forming part 10 of this specification.

My invention relates to what is known as pocket windows in which a pocket is provided in the upper portion of the sash frame for the reception of the sash to give 15 a free and unobstructed window opening, provision also being made for window screens located outside the sash and also adapted to be pushed up into the window pocket either to obtain access to the sash, 20 or for winter storage of the screens when their use is not required.

It is the object of my present invention to provide in connection with such windows for a storm window construction.

25 Heretofore wherever storm windows have been desired during the winter months, it has been necessary to fit into the window opening an extra sash which has to be secured in place temporarily for the winter 30 season, a matter of considerable expense, both for installation and removal. It is the object of my present invention to provide a storm window construction in which the storm window sash can be permanently 35 mounted in the window casing and pushed up out of the way when not in use.

I also provide in this connection a certain 40 novel construction for applying and mounting the weather strip for the cross rails of the sash, which obviates the special fitting of the weather strip and with which accuracy in mounting the strip so as to obtain a perfect closure is readily attained.

I also in connection with the sash provide 45 for a spring check on the sash to prevent the throwing up of the sash too rapidly against the head piece of the casing.

These various features and other points 50 of novelty will be hereinafter particularly pointed out and claimed.

In the drawing, Figure 1 is a vertical longitudinal section of my improved window construction.

Fig. 2 is a transverse section of a portion of one of the side stiles, taken on the line 55 A, A, of Fig. 1.

Fig. 3 is a detail longitudinal section, taken on the line B, B, of Fig. 2.

The pocket window is provided with the usual lower and upper sliding sashes 1, 2, 60 with the meeting rails 3, 4, the sashes being mounted in side stiles 5, 6, provided with the inside and outside beads 7, 8, with the parting bead 9 for the two sashes, sill 10 and head piece 11. The sash stiles run 65 to the top of the pocket above the window opening and the head piece closes the pocket top, while the front of the pocket is in the construction illustrated formed of corrugated sheet metal 12 suitable for plastering. 70 The outer wall of the pocket is inclosed by sheeting 13, over which the weatherboarding 14 or other outside finish is secured.

The window casing is also provided with the finish 15 and the sill piece 16. The 75 sashes are provided with the usual sash cords 17, 18, which run over sash pulleys 19 at the head of the stiles and to the sash cords are attached the usual weights in the weight box behind the stiles. Outside of 80 the sash stiles is the sheet metal channel strip 20, one on each side, to serve as a guide for the window screens. These screens are preferably metal frames, 21 for the lower sash and lower frame, and 22 for the upper, with wire screening 23, 24, for the respective screens. As illustrated, a flanged 85 strip is provided for the top rail of the lower screen to confine it between the upper and lower rails of the upper screen while the upper rail of the upper screen is formed of double thickness to fill out the opening in the guideway. An angle plate 25 is secured along the outer face of the bottom cross rail of the lower screens to provide a 90 bearing on the sill when the screen is down and to project underneath the outside lower edge of the pocket when the screen is raised, so as to close the opening. The screens when pushed up into the pocket are held in 95

100

place by any suitable means such as the spring plate 26 shown in Fig. 1.

To provide for the storm window construction, an additional sash runway 27 is formed on the stiles 5 running from the head piece to the sill which is provided in the casing with the parting bead 28 and formed at the outside by the inner bead 7, hitherto referred to. Mounted in this additional runway is an additional sash 30, provided with the sash cord 31 and the sash pulley 32 at the head of the stile.

To form an effective closure of the window pocket and ordinary sash, great care must be taken that the weather stripping for the cross rails of the additional sash shall fit accurately. On the upper rail is secured the weather stripping support 33, provided with a strip of felt 34 projecting beyond the face of the support strip 33, and when the additional sash is drawn down opposite the upper sash, this felt strip 34 has a close bearing along the bearing strip 35. In order that an accurate fit may be obtained, a shoulder 36 is provided for the lower face of the strip 33, with a corresponding shoulder on the upper surface of the upper rail, and these shoulders will insure when properly cut a snug bearing of the felt 34 on the bearing strip 35. This weather strip fills up the space between the side of the sash and the upper cross piece 37 of the inside bead which space is left in order to prevent this bead from marring the outer surface of the sash when raising or lowering the same.

At what corresponds to the meeting rails 3, 4, of the ordinary sash, that is the cross rail 38, there is also provided a felt strip 39 which bears against the inlaid bearing strip 40 carried by the upper rail 3 of the sash 1, so that when the rails 38 and 3 are opposite each other, there shall be a tight closure between these cross rails.

With a pocket window construction, inasmuch as the sashes run up for their full length into a pocket, it is found that with a well-balanced sash, in raising the sash the user is very apt to give such a momentum to the sash as to cause it to strike with a considerable blow against the head piece and the sash lights are liable to be broken by the jar, or the sash otherwise damaged. In order to check this movement and serve as a brake in raising the sashes into the window pocket, I therefore secure in the pulley stile so as to bear against the side front face of the sash on each side, spring metal strips 41, which bear against the side members of the sash and act as a very effective brake and check the movement. As illustrated in the drawing, I have applied these spring strips in the path of the additional sash, but for each of the other sashes similar strips may be mounted.

65 In fitting the weather strips for the cross

70 rails of the sash by reason of the fact that the shoulders can be accurately cut both in the weather strip and the top surface of the cross rail, the weather strips can be fitted with the greatest accuracy. In the ordinary construction where the weather strip is merely secured on top of the cross rails without any positive guide and stop, a very slight variation in attaching the strip will throw the felt material out of perfect alinement 75 with the bearing strip with which it is to make contact.

78 It is thought that from the foregoing description, the use and advantages of my invention will be obvious.

80 It is intended to construct and ship the entire casing with all its parts properly fitted as a single package.

85 Except during the winter months the additional sash will be pushed up into the pocket and will be entirely out of the way. The lower sash is provided with weather stripping 42 to furnish an accurate fit at the base and this lower sash can be raised or lowered, and the two ordinary sashes used as 90 usual by merely raising the storm sash temporarily. With the accurate fitting of the weather strip material and the complete closure of the pocket opening by the additional sash, I have found that it is not necessary to 95 provide any lower storm sash, and that the single sash shown serves sufficiently to meet all the exigencies of the weather. The air space between the upper sash and the additional sash very effectively prevents radiation as well as the entrance of air around the joints.

100 Having thus described my invention, what I claim as new and desire to secure by Letters Patent, is:—

105 1. In a pocket window construction, a window frame with upper and lower sashes mounted to slide therein, and into the pocket, with the upper sash located and adapted to close the space between the lower sash and the outer wall of the pocket at the mouth thereof, and an additional sash mounted to slide in the frame and into the pocket, and positioned and adapted to close the space 110 between the lower sash and the inside wall of the pocket at the mouth thereof.

115 2. In a pocket window construction, a window frame with upper and lower sashes mounted to slide therein, and into the pocket, with the upper sash located and adapted to close the space between the lower sash and the outer wall of the pocket at the mouth thereof, and an additional sash mounted to slide in the frame and into the pocket, and positioned and adapted to close the space 120 between the lower sash and the inside wall of the pocket at the mouth thereof, and weather sealing devices intermediate the rails of the additional sash and the pocket wall.

3. In a pocket window construction, a window frame with upper and lower sashes mounted to slide therein, and into the pocket, with the upper sash located and adapted to close the space between the lower sash and the outer wall of the pocket at the mouth thereof, and an additional sash mounted to slide in the frame and into the pocket, and

positioned and adapted to close the space between the lower sash and the inside wall 10 of the pocket at the mouth thereof, and weather sealing devices for the said upper end and the said additional sash, forming a wiping contact with the said inner and outer walls of the wall pocket at its said mouth. 15

EDMUND H. LUNKEN.
